HOT AIR FURNACE

Charles M. Snelling, Jr., Greenville, S. C.

Application December 8, 1933, Serial No. 701,501

12 Claims. (Cl. 126—109)

This invention relates to what is generally termed, a hot air furnace for heating buildings and the like.

It is an object of this invention to provide a hot air furnace having a greater amount of heating surface than any type of furnace heretofore developed, and this object is obtained by having a fire box surrounded by an air space into which the unheated air is drawn and the air is heated and then passed upwardly and spirally through a compartment while the direct heat from the fire box is passed also through this compartment but separated from the heated air. On top of this compartment is mounted a distributing head which receives the heated air and distributes it to the various rooms of the building being heated. An important feature of the invention is a space between the heated compartment and the distributing head so that if one of the pipes to a room is rendered inoperative, that is by the heat being cut in that room, the heat will be distributed to the other rooms and thus injury to the furnace will be eliminated because there will be no dead air space in the heated portion of the compartment disposed above the fire box.

It is another object of this invention to provide a hot air furnace having a fire box with an enclosed air space surrounding the same and a unit mounted above the fire box through which the flames and direct heat can pass, said unit having a plurality of pipes therein whose lower ends communicate with the air space surrounding the fire box and whose upper ends pass through the upper end of the unit mounted above the fire box; also a distributor casing is mounted above the upper end of the said unit providing a compartment between the distributor casing and the said unit into which the heated air passing through said pipes empties, and said distributor unit has a plurality of pipes leading therefrom and whose lower ends communicate with said air space above the upper end of said unit. In this manner a structure is provided in which it is impossible for one of the delivery pipes leading to the rooms of the building to appropriate more than its share of the warm air, as is common in some types of furnaces. On account of the pipes in the middle unit of the device, emptying into an air space disposed below the distributor casing, it is therefore seen that the heated air passes into a common chamber from whence it passes into the delivery pipes of the distributor casing, and thus it is seen that all of the air will not pass through one pipe because all pipes communicate with said air space into which the heated air is delivered.

It is to be understood that the material from which the apparatus is constructed can be chosen to suit the particular need, for it will be evident that the casing surrounding the fire box could be of a heavy grade of sheet metal and also the distributor casing and delivery pipes can be of a heavy grade of sheet metal, whereas the middle unit, which is exposed to the direct action of the heat, as well as the fire box, would have to be of cast-iron and the like to withstand the direct action of the heat.

It is also to be understood that though I have described the source of heat throughout, as being a fire box, it is evident that a source of electrical heat or oil heat or any other desired heat producing means may be disposed where the fire box is shown in the drawings.

Some of the objects of the invention having been stated, the invention will appear more fully in the detailed description hereinafter following, when taken in connection with the accompanying drawings showing a preferred embodiment of my invention, in which:

Figure 1 is an exploded isometric view of the invention;

Figure 2 is an exploded isometric view of the invention and looking in a reverse direction to that in Figure 1;

Figure 3 is an elevation of the invention with parts broken away to show the interior thereof;

Figure 4 is a transverse sectional view taken along the line 4—4 in Figure 3;

Figure 5 is a vertical sectional view taken along line 5—5 in Figure 3 through the central portion of the lower unit of the apparatus;

Figure 6 is a vertical sectional view taken along line 6—6 in Figure 4 showing the central upper portion of the middle unit of the apparatus.

Referring more specifically to the drawings, 10 indicates the outer casing of the lower unit having a flange 11 secured around the lower edge thereof, forming a suitable means for support, though it is understood that any suitable base may be substituted for the flange 11. Centrally disposed within the casing 10 is a fire box arrangement in the form of cylinder 12 having a flange 13 on the interior thereof on which is mounted a grate 14 which is conventional and is rotatable by means of an extension 15 which may be engaged by hand or a suitable tool after the extension 15 projects through a slot 15a in the outer casing 10.

The lower portion of the cylinder 12 has an opening 16 surrounded by an extension 17 which

extends through the outer casing 10 and has a flange 18 thereon supporting an ash door 19.

Also disposed above the grate 14 is an opening 20 surrounded by an extension 21 which extends 5 through the outer casing 10 and has a flange 22 thereon supporting a fire door 23.

Disposed on the inside surface of the casing 10 is an annular trough 24 into which water may 10 be placed through a funnel member 25 for supplying humidity to the heated air.

The casing 10 has opposed extensions 26 and 27 to which are connected pipes 28 and 29 which 15 pipes form the intake pipes for the air to be heated and passed to the desired rooms of the building. The pipes 28 and 29 may extend to any suitable portion of the building for returning the air from the rooms back to the heating unit.

The pipes 28 and 29 have pivotally mounted 20 therein dampers 30 and 31 which have levers 32 and 33 mounted on the exterior of the pipes 28 and 29 to which operating means such as chains 34 and 35 are secured which are extended to any 25 suitable portion of the building for regulating the amount of air drawn into the compartment between members 10 and 12. These dampers are limited by stops 36 and 37 but it is to be noted that when the operating means 34 and 35 are not rigid the draft being drawn through pipes 28 and 29 may rotate the dampers and draw the 30 lower portion thereof inwardly towards the compartment to regulate the amount of air which is drawn into the casing 10. If desired, of course chains 34 and 35 may be replaced with rigid connections so as to rigidly control the dampers 35 30 and 31.

The upper portion of cylindrical member 12 has a flange 38 therearound, acting as a support 40 for the central portion of the plate 40 which forms the bottom of the next unit.

40. The next unit which is mounted on top of casing 10 and of which plate 40 forms a bottom portion, comprises a cylindrical portion 41 having a band 42a welded thereto and which fits over the outside of the casing 10. The plate 40 is 45 flanged along its periphery and is suitably secured to casing 41. The plate 40 has a hole in the center thereof into which the upper end of cylinder member 12 fits to form an air-tight joint between plate 40 and flange 38.

50. The upper end of cylinder 41 is closed by a plate 42 which has secured to the upper surface thereof a ring 42b of slightly smaller diameter than the cylindrical portion 41, thus forming a shoulder 44 on the upper end of cylinder 41. The 55 plates 40 and 42 support the ends of a plurality of spirally disposed pipes 43 and it is to be noted that pipes 43 at their upper ends are so disposed that their cross-sectional longitudinal axes are radially disposed with regard to the casing 41. 60 These pipes 43 are spaced apart from each other to allow the flame and smoke from the fire box to pass therebetween. By having the pipes 43 arranged spirally, a greater surface is exposed to the heat generated by the heat producing means than if the pipes 43 were vertically disposed. It also gives a swirling motion to the 65 heated air which swirl is in a direction which is the same as the direction of the outlet pipes 59, hereinafter described, and it is to be noted that the outlet pipes 59 are also spirally arranged in the same direction as the pipes 43, whereby the swirling motion given to the heated air by pipes 43 is continued as the air, after leaving pipes 43 in a swirling manner, enters the outlet pipes 70 which are spirally arranged in the same direc-

tion, thus obtaining quite a distinct advantage over and above pipes arranged vertically or horizontally, because if the pipes 59 were otherwise arranged, there would be a sharp turn necessary in the heated air whereas, by having both pipes 43 and 59 spirally arranged in the same direction, no appreciable obstruction is offered to the passage of the air and greater efficiency is obtained. 5

It is to be noted that the plate 42 has a centrally disposed hole therein which is closed by a tubular portion 45 which projects downwardly and also projects through the central portion of a plate 46. The lower end of tubular portion 45 has enlarged portion 47 to which is secured 10 a cone 48.

The purpose of the above recited arrangement is to close the upper ends of the portion of the cylinder which receive direct heat from the fire box and the cone 48 deflects these air currents 20 from the fire box outwardly.

It is to be noted that plate 46 has a plurality of openings 50 through which the pipes 43 pass, the openings 50 being somewhat larger than the pipes as these openings 50 form the sole passage-way for the flames, heated air currents and smoke passing upwardly from the fire box 12. This arrangement forces the heated air and flames arising from the fire box 12 to pass into close contact with the pipes 43 to heat the air passing 30 therethrough. Secured to the casing 41 and communicating with the space between plates 42 and 46 is a pipe 51 which is connected to a smoke stack, chimney and the like, thus completing the draft arrangement for allowing the smoke from 35 the fire box to pass into a suitable chimney.

Adapted to fit immediately outside ring 42b on the upper end of casing 41 is a distributor head which comprises a casing 55 which has a plurality of radially disposed vanes 56 spaced apart from each other and to the inside ends of these vanes a cylinder member 57 is secured having a centrally disposed opening therein in which is slidably mounted a pipe 58, this pipe being held in frictional sliding movement within the cylindrical member 57 so that it can be adjusted vertically. This pipe may be connected to a pipe leading to the central portion of the building so that if all of the rooms should be cut off from the furnace the furnace would not be damaged because the 50 air would pass into the central portion of the building to which pipe 58 leads. 45

It is to be noted that the lower ends of vanes 56 do not extend down to the plate 42, thus leaving a space between the lower end of the vanes 55 56 and the plate 42. This is provided so that when some of the pipes leading to the rooms of the building are cut off to prevent heat from going to these particular rooms it will not prevent circulation of air in the pipes 43 because all 60 of these pipes 43 discharge their heated air into the compartment between the plates 42 and the lower portion of the vanes 56 and therefore, the heated air will pass into the other pipes which are not disconnected from their rooms and in case all pipes were disconnected from their rooms, then the heated air would pass through pipe 58 to the central portion of the building. 65

It is also to be noted that the vanes 56 form the 70 bottom portion of the discharge pipes 59 where as, a shorter vane 60, (see Fig. 3) forms the upper side of the pipe 59 and is joined as at 61 to the lower surface to the next succeeding vane 56, thus forming the plurality of pipes 59 to which 75

are secured suitable piping which leads to the various rooms of the building.

It is to be noted that pipe 58 can be adjusted vertically to determine the amount of air which is allowed to be conducted to the central portion of the building and of course a suitable damper, not shown, can be provided in the building for cutting off the pipe 58 entirely and forcing the heated air through the pipes 59 is desired.

10

Method of operation

Air enters through pipes 28 and 29 into the compartment between cylinders 10 and 12 and on account of the fire on grate 14 the air is heated within this compartment and is also humidified and passes upwardly through pipes 43. These pipes are spirally arranged and spaced apart from each other. The heated air empties from pipes 43 into the compartment immediately above plate 42 and passes into the pipes 59. It is noted that when any one of the pipes 59 is disconnected from the room, to which it leads, the air will pass into the other pipes which will still establish a circulation through all of the pipes 43 because it is discharging into a common compartment disposed between casings 41 and 55.

The heat draft arising from the source of heat in casing 12 passes upwardly into the central portion of casing 41 and is forced outwardly around pipes 43 and passes through the openings 50 surrounding pipes 43 and into the compartment between plates 42 and 46 and from thence passes through pipe 51 to the smoke stack. This causes the air passing upwardly through pipes 43 to be further heated by this draft and it is to be seen that a large heating surface is provided on account of the arrangement of the pipes 43.

Another important advantage is that if the pipes 59 were directly connected to pipes 43 and if the damper of a particular room were closed it would prevent circulation of air upwardly through that particular pipe 43 and the heat from the fire box would damage that particular pipe, but on account of all of the pipes 43 discharging into a common compartment it is seen that in case any pipe 59 is closed that the other pipes will take the heated air to the other rooms and thus all of the pipes 43 will have air circulation therethrough at all times.

Another important advantage of this invention is that it provides a much greater amount of heating surface to the size of the furnace than is present in any furnaces heretofore developed.

The position of pipes 43 can be varied in accordance with the heating surface desired. They can be arranged vertically or can be arranged in flat spirals to secure a greater heating of the air passing therethrough. The pipes 43 can be round, oval or of any desired shape, the drawings being merely illustrative of one form of the invention.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. A heating unit comprising a base member, a heat producing unit disposed within the base and of substantially smaller dimensions than the base thus forming an air chamber between the base and the heat producing unit, a middle unit disposed on top of the base and having a plu-

rality of spaced and spirally arranged pipes therein, the lower ends of the pipes communicating with the space between the heat producing unit and the walls of the base member, a third unit fitting onto the upper end of the middle unit and having a plurality of pipes leading upwardly and spirally therefrom and spiraled in the same direction as the other spirally arranged pipes, a pair of header plates closing the upper and lower ends of the said second unit, the two header plates in said second unit having the spirally arranged pipes communicating therethrough and a draft vent extending from the upper portion of said second unit immediately below the header plate in the upper end thereof.

2. A hot air furnace having a fire box and a casing disposed around the fire box and forming an air space between the casing and the fire box, a middle casing disposed on the upper end of the first casing and closing the upper end of said air space, means closing the upper and lower ends of the middle casing, the lower end of the middle casing having a hole therein into which the upper end of the fire box is fitted, a plurality of spirally arranged pipes extending entirely through the middle casing and having their lower ends communicating with the air space in the first casing, a draft vent communicating with the upper portion of the sidewall of the middle casing, a distributing casing mounted on the upper end of the middle casing and having a plurality of spirally arranged pipes spirally arranged in the same direction as the first mentioned spirally arranged pipes and extending therefrom and having their lower ends spaced from the upper ends of said pipes in the middle casing.

3. A warm air furnace having a firebox and a casing surrounding the fire box and providing an air heating space between the casing and the fire box, a second casing disposed over the upper end of the first casing, a header plate closing the upper end of the second casing, an annular member closing the outer portions of the lower end of the second casing, a distributor casing disposed over the upper end of the second casing and having a plurality of spirally arranged pipes extending therefrom and open at their upper and lower ends, a plurality of pipes in the second casing spirally arranged in the same direction as the first mentioned spirally arranged pipes and communicating through said header plate and said annular member, a draft vent in the upper side portion of the second casing, the heated air passing through said spirally arranged pipes and through said distributor casing and the draft through the fire box passing centrally upwardly and then outwardly through said second casing.

4. A warm air furnace having a plurality of spirally arranged air pipes and having a plurality of other spirally arranged distributing pipes disposed above the upper ends of the air pipes and extending in the same direction as the first mentioned spirally arranged pipes, the lower ends of the distributor pipes stopping short of the upper ends of the air pipes to form a compartment for the air after passing through the air pipes and before the air enters the distributor pipes, and means for heating the exterior of the air pipes to heat the air passing therethrough.

5. A warm air furnace having a fire box and an enclosed air space surrounding the fire box, a casing closing the upper end of the air space but communicating with the upper end of the fire box, a header plate closing the upper end of

the casing, a distributor casing disposed on the upper end of the casing, a plurality of spaced and spirally arranged pipes in the first-named casing communicating with the air space at their lower ends and through said header plate with the distributor casing at their upper ends, a disk intermediate the ends of the first-named casing and having a plurality of holes therein larger than the pipes and through which the pipes are passed, the distributor casing having a plurality of pipes arranged therein spiralled in the same direction as the first spirally arranged pipes and whose lower ends are spaced from the upper ends of the first spirally arranged pipes and forming an air chamber between the ends of the two sets of pipes, whereby flames and products of combustion are adapted to pass around said first pipes and through said openings in said intermediate disk, and a draft vent in the sidewall of the casing and communicating with the space above said intermediate disk.

6. A warm air furnace having a casing provided with a plurality of spirally arranged pipes therein, means for heating the exterior of said pipes, means for conducting air to be heated through said pipes, and spirally disposed means extending in the same direction as the first spirally arranged pipes for conducting the heated air in divergent directions after it leaves said first pipes.

7. A warm air furnace comprising a casing, a plurality of spirally arranged pipes passing through said casing, means for supplying partially heated air to the lower ends of said pipes, a distributing casing enclosing the discharge ends of said pipes and having spirally arranged distributing pipes extending in the same direction as the first spirally arranged pipes for distributing the air after it has passed through said first pipes, the distributing casing forming a compartment immediately above the upper ends of said first pipes.

8. A warm air furnace comprising a source of heat, a casing surrounding said source and forming an enclosed air space surrounding said source, a second casing disposed above said source and having a plurality of spirally arranged pipes passing therethrough, the lower ends of said pipes communicating with said enclosed air space, a distributor casing having a plurality of other spirally arranged pipes therein extending in the same direction as the first spirally arranged pipes, surrounding the upper end of said second casing and forming an enclosed air space above the upper end of said second casing into which the upper ends of said pipes discharge air, a draft vent in said second casing and a plate disposed in said second casing below said draft vent and having openings therein larger than the pipes through which openings said pipes are led whereby draft currents from said source are passed in close proximity to the exterior of said pipes.

9. A warm air furnace comprising a fire box, a casing surrounding the fire box and in spaced relation thereto forming an air space between the fire box and the casing, a second casing disposed above the first casing and closing the upper end of the first casing but leaving the upper end of the fire box open, a header plate closing the upper end of the second casing, a plurality of spirally

arranged pipes having their upper ends communicating through said header plate in the upper end of the second casing and having their lower ends in communication with the air space surrounding the fire box, a distributor head mounted on top of the first casing and forming an air space between the upper end of the second casing and the distributor casing into which the air passing through said pipes enters, a draft outlet in the sidewall of the second casing and means for directing the flames and heated air from the fire box in close proximity to the outer surfaces of said pipes and outwardly through the said draft outlet, said distributor head having discharge pipes spirally arranged in the same direction as the said spirally arranged pipes.

10. In a warm air furnace, a fire box disposed centrally of the furnace and having a passageway thereabove for the products of combustion, a casing surrounding the fire box and forming an air space around the fire box, a casing disposed above the fire box and having a plurality of spirally arranged pipes therein whose lower ends are in communication with the said air space, a distributor head disposed over the second casing for receiving air drafts from said pipes, a draft outlet in said second casing for directing the products of combustion from the fire box upwardly in said second casing and against and around the said pipes therein, said distributor head having discharge pipes spirally arranged in the same direction as the said spirally arranged pipes.

11. A hot air furnace comprising upper, lower and middle casings, disposed end on end, a fire box centrally disposed in the lower casing and having an open upper end, means closing the ends of the middle casing, a plurality of concentrically arranged and spirally disposed pipes in the middle casing and penetrating the ends thereof, the upper casing having a plurality of concentrically arranged hot air pipes spiralled in the same direction as the said spirally disposed pipes in the middle casing whose lower ends are in communication with, but spaced from the upper ends of the pipes in the middle casing, the lower end of the middle casing having a hole therein through which products of combustion from the fire box may pass to strike the exterior of the pipes in the middle casing, and an exhaust pipe penetrating the sidewall of the middle casing.

12. A hot air furnace comprising a base, a fire box disposed concentrically of said base and having its upper end open, an intermediate casing mounted on the upper end of said base and closing the upper end of the base except the fire box, a closure for the upper end of said intermediate casing, a plurality of spirally arranged pipes concentrically arranged in said intermediate casing and passing through the upper and lower ends of said intermediate casing, an exhaust pipe penetrating the sidewall of said intermediate casing, a top mounted on the upper end of said intermediate casing and having a plurality of hot air pipes spirally disposed therein and extending in the same direction as the first spirally arranged pipes, the lower ends of said hot air pipes stopping short of the upper ends of said pipes in said intermediate casing to form an air space between the two sets of pipes.

CHARLES M. SNELLING, JR.
